(57) **CLAIM**

We claim the ornamental design for the disc storage locker, as shown and described.

DESCRIPTION

FIG. 1 is a front perspective view of the disk storage locker showing speaker holes of the present invention.

FIG. 2 is a rear perspective view of the disk storage locker of the present invention.

FIG. 3 is a top plan view of the disk storage locker of the present invention.

FIG. 4 is a left side elevational view of the disk storage locker of the present invention.

FIG. 5 is a front elevational view of the disk storage locker of the present invention.

FIG. 6 is a right side plan view of the disk storage locker of the present invention.

FIG. 7 is a rear elevational view of the disk storage locker of the present invention; and,

FIG. 8 is a bottom plan view of the disk storage locker of the present invention.
